UNITED STATES PATENT OFFICE.

HARRY LEIGH DAY, OF PADUCAH, KENTUCKY, ASSIGNOR OF FIVE-SIXTHS TO LINER B. LANGSTON AND ONE-SIXTH TO CHARLES E. STAVELY, BOTH OF PADUCAH, KENTUCKY.

CROSS-TIE.

1,073,406.

Specification of Letters Patent. Patented Sept. 16, 1913.

Application filed December 17, 1912. Serial No. 737,252.

To all whom it may concern:

Be it known that I, HARRY L. DAY, a citizen of the United States, residing at Paducah, in the county of McCracken and State of Kentucky, have invented new and useful Improvements in Cross-Ties, of which the following is a specification.

The present application relates to ties for railway rails.

10 In carrying out my invention, it is my purpose to provide a tie which shall be constructed of metal and which shall embody a pair of coacting elements which, when secured together, will sustain the rails either 15 in a direct longitudinal path or at an inclination or angle.

A further object of the invention is the provision of a simple but effective means for sustaining the ties against either longitudinal or lateral movement.

With the above recited objects in view and others which will appear as the nature of the invention is more fully disclosed, the improvement resides in the construction, 25 combination and operative arrangement of parts set forth and falling within the scope of the appended claim.

In the drawing, Figure 1 is a top plan view of a railroad, showing the rails supported upon and connected through the medium of my improved ties, Fig. 2 is a sectional view upon the line 2—2 of Fig. 1, Fig. 3 is a perspective view of one of the tie sections. Figs. 4 and 5 are detail plan views of one end of co-acting ties which are employed for connecting rail ends, Fig. 6 is a detail transverse sectional view upon the line 6—6 of Fig. 1, and Fig. 7 is a perspective view of one of the tie sections employed for connecting the frogs or wedges of the rails.

Referring now to the drawings in detail, the numeral 1 designates the sleepers for the ties, the same preferably embodying substantially rectangular wooden members which have their ends connected in any desired or preferred manner. Arranged transversely of the sleepers 1 are the ties 2. Each of these ties embodies a substantially rectangular metallic member, and each of the said ties is provided adjacent one of its ends with rail engaging lugs 3, while disposed upon the under face of each of the said ties, adjacent the lugs 3, are biting teeth 4 which

are adapted to be embedded within the sleepers 1. The members comprising the ties 2 are provided with lugs 5 which are arranged angularly upon the said ties and which are disposed at one of the longitudinal edges of the ties. The members are further provided adjacent their end, formed with the rail-engaging members 3, with additional lugs 6. Each of these lugs has its outer face formed to conform with the shape of the side of the rail with which it is adapted to engage. The lugs 6 are each formed with an angular face 7, the same being provided with an angular opening 9. The lug 3 is also provided with an angularly arranged opening 10, the bore of which is threaded.

As stated, the ties are of a similar construction, and it will be noted that when the coacting ties are brought together, and the rail-engaging elements 3 will contact with the opposite faces of the rails, while the members 6 will contact with the inner faces of the said rails, and further that by providing threaded elements, in the nature of bolts 12, which pass through the openings 9 and 10, respectively, the ties will be effectively connected. Furthermore, the teeth 4 of the ties, which are adapted to be embedded within the sleeper 1 will effectively prevent either the lateral or longitudinal movement of the said ties, and consequently sustain the rails in a proper position upon the ties. When the ties are to be employed for connecting the meeting ends of rails, the members 3 are engaged and provided with openings 12 for the reception of securing elements, such as nuts and bolts. At switches and other curved portions of the rails, certain of the ties have rail-engaging lugs 13 which are arranged at proper points upon the ties to receive the rails, and a separable fish plate 14 is also provided for the opposite sides or faces of the rails, to those engaged by the lugs.

From the above description, taken in connection with the drawings, the simplicity of the device as well as the advantages thereof will, it is thought, be apparent to those skilled in the art to which this invention appertains.

Having thus described the invention, what I claim is:

In a device for the purpose set forth, tie

members having their under faces formed with teeth, rail-engaging elements integrally formed upon each of the tie members, angularly arranged vertically disposed lugs 5 formed with openings and disposed adjacent the rail-engaging elements, one of the openings provided upon each of the lugs being threaded, and oppositely disposed bolt members having threaded shanks engaging

within the openings and the threads provided in the openings.

In testimony whereof I affix my signature in presence of two witnesses.

HARRY LEIGH DAY.
